REMOTE CONTROL SYSTEM

Harmon B. Deal, Glen Ridge, N. J., assignor to
Radio Corporation of America, a corporation of
Delaware

Original application July 23, 1941, Serial No.
403,736, now Patent No. 2,340,798, dated Febru-
ary 1, 1944. Divided and this application Octo-
ber 16, 1942, Serial No. 462,252

4 Claims. (Cl. 250—36)

The present invention relates generally to remote control systems, and more particularly to a remote control system wherein the operation of a radio receiver may be controlled from a remote point such as a broadcasting station. This application is a division of my application Serial No. 403,736, filed July 23, 1941, Patent No. 2,340,798, granted February 1, 1944.

It is, of course, obvious that in times of national emergency it may be of vital importance immediately to broadcast to the people of the nation, or to a certain class of people such as air wardens, an impending condition or action and to issue necessary instructions to them. To this end, it is an object of the present invention to permit a broadcasting station to turn on all receivers, or a certain group of receivers, within range which are equipped with an attachment made in accordance with the present invention, and also, to turn the receivers off. The scheme contemplated herein is feasible from all viewpoints for either the sound broadcast band or the ultra-high frequency band.

While the various features of the invention are of the greatest importance in connection with the turning on and off of radio receivers from a transmitting point, it will be appreciated by those skilled in the art that by simple extensions of the method and arrangements herein disclosed, the number of control functions may be increased to any desired extent. However, the on and off functions are, in a sense, primary and should properly precede inclusion of any additional controls which may prove desirable. Accordingly, the invention will be described in connection with a simple on and off control.

In accordance with the present invention, control signals which are preferably, though not necessarily, generated at the broadcast station are utilized to modulate the carrier of the broadcast station which is to exercise control. Of course, if desired, an auxiliary special carrier may be modulated.

If a remote receiver is to be controlled only as to on and off, and the station's regular carrier is to be modulated by the control signals, it is immaterial whether or not the controlling signals are audible since the control signals would normally precede the start, and follow the termination of the special broadcast that was the occasion for turning the receiver on. However, it is evident that under certain circumstances, an inaudible control signal is to be preferred, as for example in the case where there may have

been in progress a program to which many people were already listening and to whom an audible control signal would be objectionable, or in cases where a certain amount of secrecy is desirable.

Inaudibility of the control signal may be obtained by utilizing super-audible or sub-audible control frequencies. Since super-audible frequencies would encroach on adjacent broadcast channels, sub-audible control frequencies are preferred. Another reason for preferring the sub-audible frequency band for the control frequencies is because it is immediately available since it is not being used presently. The average radio receiver and loudspeaker cut off below 100 cycles per second, and even the very best receivers with considerable bass compensation do not transmit frequencies below 50 cycles per second to any appreciable extent. This indicates that a band in which control signals will not affect program material being broadcast simultaneously, lies below 50 cycles per second. It is recognized, of course, that the low frequency cut-off of a receiver is not abrupt, and that therefore the lowest usable frequency and amplitude of the control signals will produce the least program interference.

In a series of tests which have been conducted with devices built in accordance with the present invention, it has been found that the amplitude of the control signals should be kept as small as possible for the reason that harmonics of the control frequency, whether originating in the source or produced in the receiver, will lie in the acceptance band of the usual radio receiver and will be audible. The harmonics may be produced in the receiver by overload or by cross-modulation of control frequencies and program, and it has been determined that both of these effects are considerably aggravated by large control signal amplitude.

Briefly, the invention provides means at the transmitter for producing the control frequencies which may comprise an oscillation generator tube and modulating means for modulating the carrier of the transmitter with the control signals. At the receiver, means are provided for receiving the modulated carrier and utilizing the derived signals for control purposes. This last named means may comprise a small radio receiver which may be made very simple and inexpensive if its function is to operate only on control signals.

Referring now to the drawing, which shows a suitable control signal generating means which

may be used at a transmitting station, there is provided an electronic tube 1 which is employed as an oscillator to generate the various desired control frequencies. For this purpose a novel phase reversal circuit arrangement is used for providing phase reversal between the grid and plate of the oscillator tube 1. The phase reversal network is connected between the anode and cathode of the tube and comprises capacities 7, 8, and 9 and resistors 10 and 11. This network, also, determines the frequency of the generated oscillations in accordance with the values of the resistances and the condensers. Resistors 10 and 11 are normally shunted by resistors 14 and 13 respectively, one shunt circuit extending from a junction point 26 through a switch contact 18, through resistor 14 and thence to a junction between resistors 10 and 11. The other shunt circuit extends from a junction point 25 through switch contact 17, through resistor 13 and thence to the junction between resistors 10 and 11. Feedback between the plate and the grid is provided by a circuit 24 which connects point 26 of the phase reversing circuit to the input grid of tube 1 through a coupling condenser 3. In order to avoid undesirable phase shifts in the resistance of the grid coupling circuit, a high resistance grid leak resistor 2 is provided.

Preferably the resistance of resistor 2 should be large as compared to the reactance of condenser 3. Two control push buttons 16 and 20 are provided. Push button 20 acts upon depression to close a switch 21, and thereby connects the output of the oscillator 1 to the amplifier 23. Push button 16, on the other hand, acts when depressed to open switches 17 and 18 and close switch 19. Normally resistor 13 is connected in parallel with resistor 11, and, likewise, resistor 14 is connected in parallel with resistor 10. Under these conditions the net resistance between points 25 and 26 of the network is decreased. This results in a higher frequency of oscillation. Consequently, with push button 16 not depressed, and push button 20 depressed, control oscillations of a certain frequency are impressed upon the amplifier 23 through closed switch 21 and conductor 22.

When push button 16 is depressed, the parallel resistors 13 and 14 are disconnected from the phase shifting circuit thereby resulting in a higher net resistance between points 25 and 26 and therefore providing a lower output frequency, it being noted that the new frequency is fed to the same output amplifier 23 through conductor 22 due to closure of switch 19. In the condition shown, the oscillator 1 is operating at a frequency which is determined by resistors 10, 11, 13, and 14, and the oscillations of this frequency will be impressed upon the amplifier 23 upon closure of switch 21. Hence, depression of push button 20 will impress this control frequency upon the transmitter where it is utilized to modulate the carrier of the transmitter in accordance with well known practice.

It should be noted that resistors 10, 11, 13, and 14 are preferably variable resistors so as to permit adjustments. Also, unicontrol means 12 is provided to adjust resistors 10 and 11 simultaneously, and unicontrol means 15 is provided to permit simultaneous adjustments of resistors 13 and 14. If it is desired to transmit the other control frequency, it is only necessary to depress push button 16 as previously described.

While I have indicated and described a system

for carrying my invention into effect, it will be apparent to one skilled in the art that my invention is by no means limited to the particular organization shown and described, but that many modifications may be made without departing from the scope of my invention, as set forth in the appended claims.

What I claim is:

1. In an oscillator system of the type provided with a tube having at least a cathode, a control grid and a plate, a phase reversal network connected between the plate and cathode, said network consisting solely of resistive and capacitive elements, means for varying the number of resistive elements to be included in said network, thereby to shift the network's frequency characteristic from one to the other of two predetermined values, a feed back circuit connected between the output terminals of the reversal network and the grid, and a pair of push button switches, one of said switches constituting means for applying oscillatory energy of one frequency to a utilization device and for switching out of said network certain of its resistive elements, and the other of said switches constituting means for applying oscillatory energy of the other frequency to said utilization device while the full complement of resistive elements is retained in said network.
2. In an oscillator circuit for producing sub-audible modulation frequencies for a high frequency carrier, a tube having at least a cathode, an anode, and a control electrode, a frequency-determining circuit connected between the anode and cathode, said circuit consisting of at least a pair of series-arranged resistors, a respective condenser connected from each resistor terminal to the cathode, a feedback connection from the output terminal of said resistors to said control electrode, and manually controllable means including two push button switches so organized that one of them increases the resistance value of said resistors and also feeds a predetermined one of said modulation frequencies to a utilization device, whereas the other of said switches operates solely to feed another of said modulation frequencies to said utilization device.
3. In an oscillator circuit for producing sub-audible modulation frequencies for a high frequency carrier, a tube having at least a cathode, an anode, and a control electrode, a frequency-determining circuit connected between the anode and cathode, said circuit comprising a pair of series-arranged resistors, and three condensers, each condenser being connected from the cathode to a different one of the resistor terminals, a feedback connection from the output terminal of said resistors to said control electrode, a second pair of series-arranged resistors, means including normally closed switch contacts for connecting in parallel the two pairs of resistors, thereby to produce a certain frequency response in said frequency determining circuit, push button means for opening said contacts, thus producing a different frequency response, said push button means being also effective to close an output circuit from said frequency determining circuit to a utilization device, and additional push button means for closing said output circuit while the closure of said switch contacts is maintained.
4. In an oscillator circuit for producing sub-audible modulation frequencies for a high frequency carrier, a tube having at least a cathode, anode and control electrode, a frequency determining circuit connected between the anode and

cathode, said circuit consisting of two parallel-connected pairs of series-arranged resistors, condensers connected from each terminal of the resistor pairs and from an intermediate junction thereof to the cathode, a feedback connection from output terminal of said resistors to said control electrode, said resistors and condensers being chosen in magnitude to cause said oscillator to produce oscillations of one or another of two predetermined sub-audible frequencies, a resistance of high magnitude connected between the control electrode and cathode to avoid undesirable phase shifts, and means including push button control switch contacts arranged in two groups such that a first group controlled by one push button comprises normally closed pairs of con-

15 tacts which constitute interconnections between the terminals of said resistor pairs, and when opened said contacts isolate one said resistor pair from the frequency-determining circuit, said 5 switch contacts of that group also including means for feeding oscillatory energy to a utilization device, the other of said contact groups being arranged for operation by a second push button and constituting means operable solely to 10 feed oscillatory energy to said utilization device during the parallel-connection of said resistor pairs, whereby one or another of two predetermined sub-audible frequencies is delivered to said utilization device.
